UNITED STATES PATENT OFFICE.

CLARENCE J. WEBER, OF CHICAGO, ILLINOIS, ASSIGNOR TO NATIONAL BRICK COMPANY, OF CHICAGO, ILLINOIS, A CORPORATION OF ILLINOIS.

TRANSPORT MEANS FOR BRICKS AND THE LIKE.

Application filed October 8, 1925. Serial No. 61,178.

This invention relates to transport means for bricks and the like, more particularly to means for delivering raw bricks selectively to the desired channels of a suitable dryer and for moving them into, through, and from the dryer, and its objects are the provision of a simplified and improved means for doing this expeditiously and with little labor and few attendants.

According to my invention I employ a transfer car which is adapted to receive the material car and to convey same selectively to any of a number of desired positions along the dryer. I provide the transfer car with suitable winch means and at the several positions to which the material car is adapted to be conveyed by the transfer car, means are provided for co-operating with a flexible element with which the winch means is provided. The flexible element is adapted to be connected or engaged with the material car, and when so engaged and placed in co-operation with the co-operating means at the position into which the car is moved, operation of the winch means moves the material car from the transfer car and into, through, and from the dryer. The means for conveying or transporting away the dried bricks is simple and is adapted for expeditious operation to complete the system.

In order to acquaint those skilled in the art with the manner of constructing and practicing the invention, I shall now describe a particular embodiment of the same in connection with the accompanying drawings, in which:

Figure 1 is a more or less diagrammatic top plan view of a system embodying the invention;

Fig. 2 is a transverse section taken on the line 2—2 of Fig. 1;

Fig. 3 is a fragmentary top plan view, partially in section, showing the transfer car, one of the channels through the dryer, and the manner of moving the material car from the transfer car and into, through, and from the dryer;

Fig. 4 is an enlarged side elevational view of the transfer car;

Fig. 5 is a side elevational view of the material car; and

Fig. 6 is an elevational view of the flexible element which is wound by the winch means for the purpose of moving the material car.

In the particular system which I have selected for the purpose of illustrating my present invention, the clay or raw brick, molded to the desired form in two dimensions, is fed in continuous formation from the brick machine 5 to the chopper or cutter 6, as by means of a suitable belt conveyor 8.

The chopper or cutter 6 cuts the continuous strip of clay or raw brick material 9 into bricks of the desired length, which are thereupon fed upon a conveyor 10, which may be of the belt type as shown. By driving the conveyor 10 at a speed in excess or greater than the speed of the conveyor 8, the bricks are separated longitudinally as shown in Fig. 1, so that they will not cling together and may be conveniently handled. Stationed along the conveyor 10, as illustrated diagrammatically at 12, are a large number of laborers or hackers who remove the bricks from the conveyor 10 and pile or stack the same on material cars 15. The dryer is illustrated more or less diagrammatically at 16. Extending longitudinally along the dryer 16 are tracks 18 and mounted upon and operable along these tracks 18 is a transfer car 20. The cars 15, adjacent the hackers' position, are mounted upon and movable along tracks 22, which tracks 22 extend transversely with respect to the tracks 18 and are adapted to meet the transfer car at substantially right angles. A series of tracks 24 extend transversely through the dryer 16, meeting the transfer car 20 at substantially right angles at one side of the dryer and adapted to meet a second transfer car 25 at the opposite side of the dryer. The transfer car 25 is mounted upon and movable along tracks 26 which extend longitudinally along the opposite side of the dryer 16 and may be substantially parallel with the tracks 18.

Mounted upon the transfer car 20 and extending transversely across the top thereof is a pair of tracks 28 which tracks by movement of the car 20 are adapted to be placed in registration with the adjacent ends of the tracks 22 or with the adjacent ends of any of the numerous pairs of tracks 24. In order that proper registration may be effected so that the tracks 28 will form continuities of the tracks 22 or 24 for the purpose of permitting the cars 15 to be rolled along the tracks 22 and directly onto the tracks 28 on the car 20 or from the

2
tracks 28 and directly onto any of the numerous pairs of tracks 24, the tracks 18 may operate in a channel or depression 30 or the tracks 22 and 24 may be otherwise elevated with respect to the tracks 18 to dispose them in the same horizontal plane with the tracks 28.

The interior of the dryer 16 may be divided into a number of transversely extending 10 passages by transverse walls 32, as shown in Fig. 3. The purpose of this is usually to eliminate the necessity of firing or heating up the entire dryer whenever it is desired to only use a part of the same. The end 15 openings 34, into and from the transverse passages through the dryer, may be closed by doors 35 hinged to be swung open or closed or of any other suitable or preferred form.

20. The car 20 comprises a flat platform 40 mounted upon wheels 42 which track upon the tracks 18. The tracks 28 extend transversely across the intermediate portion of the top of the platform 40, and to one end of the tracks 28 is a suitable electric motor 43 mounted upon the platform 40 with its axis extending vertically, and having suitable winch means 45 to be driven thereby. The motor 43 is preferably self-enclosed. 25
30 Mounted upon the opposite end of the platform 40 is an electric controller 48 having a controller handle 50.

The car 20 may be propelled along the tracks 18 electrically or otherwise, as desired. Where an electric drive is employed, the car 20 may be provided with a trolley 35 for co-operation with a suitable overhead wire. The controller handle 50 has two positions A and B. In one of these positions the electric drive for the car is adapted to be turned on to propel or drive the car along the tracks 18, whereas in the other position the electric car drive is turned off and the drive to the winch means 45 started 40 to drive said winch means by means of the electric motor 43 and wind the flexible element 52 thereon.

45. The flexible element 52 comprises a length 53 of rope or similar material and a length 58 of cable 54 or similar material, joined together at 55. The free end of the rope section 53 is secured at 56 (Fig. 4) to the winch means 45 as by wrapping it about the same, and the free end of the cable length 54 is provided with a hook 58 for fastening or attachment to the cars 15. The length of rope portion provides sufficient flexibility for proper winding upon the winch, whereas the cable portion of the flexible element imparts relatively great strength where it is most desired.

Along the tracks 24 and adjacent the openings 34 along the inlet side of the dryer, which is the side along which the tracks 18 extend, are pulleys 60, one mounted adja-

cent each inlet opening. The mounting of these pulleys 60 may conveniently be by means of brackets 62 upon the transverse walls or partitions 32 extending through the dryer.

70 The cars 15 comprise horizontal platforms 63 having end stakes or members 64 between which the bricks 65 are piled or stacked, as shown in Fig. 5. The platform 63 is mounted upon wheels 68 which track 75 upon the tracks 22, 28 and 24.

In operation the molded strip of clay or raw brick material, which issues from the brick machine 5, is chopped or cut into bricks of the desired length by the chopper 80 or cutter, and the raw cut bricks pass onto the conveyor 10, where they are separated lengthwise. From the conveyor 10 the raw bricks are removed by the hackers 12 and properly piled or stacked in the cars 15. 85 Then, by moving or propelling the transfer car 20 along the tracks 18 to register its tracks 28 with the tracks 22, one of the loaded cars 15 may be moved or propelled in any suitable manner along the tracks 22 and 90 onto the tracks 28 of the car 20. Then, by moving the car 20 along the tracks 18, its tracks 28 may be registered selectively with any of the tracks 24, so that the car 15 may be moved transversely into any desired part 95 of the dryer.

The space between the dryer and the tracks 18 is preferably such that two cars 15 may, for example, be placed or stored between the dryer and the tracks 18. 100 Assuming that the dryer or the particular transverse passage to which the car 15 is to be delivered is full or loaded with cars transversely to the dryer, then by training the flexible element 52 about the pulley 60 105 adjacent the passage to which the car is to be delivered, looping the free end of the flexible element back and attaching its hook 58 to the car 15 on the car 20, as by engaging it over the rear edge of the platform 63 110 thereof and throwing the controller to start the winch 45, the flexible element will be wound thereon and will move the car 15 from the car 20 onto the particular branch track 24 selected, moving the cars ahead of it through the dryer, and the car at the opposite end out onto the tracks 24 between the opposite side of the dryer and the tracks 26, which are preferably spaced from the outlet side of the dryer to permit storage 115 of the two cars between them and the dryer on the outlet side. In case there are no cars at all on the branch track 24 selected the car 15 may, of course, be simply moved from the car 20 and onto the tracks 24 between 120 the dryer and the tracks 18 in this manner, or it may be moved further as desired. The permitted storage and the further use 125 permitted of the car 20 takes the greatest advantage of the space available, it being 130

apparent that when the system is operating at its full capacity the dryer will always be filled with all of the tracks 24 between the dryer, and the tracks 26 occupied with 10 cars of dried bricks awaiting removal, and all of the tracks 24 between the tracks 18 and the dryer being occupied with cars of raw un-dried bricks awaiting delivery to the dryer. While that, of course, is unimportant and may be varied to suit the installation employed and to secure any desired balance, the winch and motor unit is, in the embodiment shown, mounted to one side of the car 20, and for the purpose 15 of balancing the opposite side, especially under the action of the winch when it is under load, a suitable weight 70 is mounted upon the platform 40 on the side of the car opposite the winch.

20 For the purpose of removing or conveying away the dried bricks, the transfer car is operable along the tracks 26 to receive the material cars 15 selectively from the tracks 24 and to convey the material cars 25 15 selectively to a plurality of branch tracks 72. A crane element, or the like (not shown) is adapted for removing the stacked bricks from the cars 15 on the tracks 72 and for carrying them to the kiln 75. By means of the transfer car 25 the empty cars 15 are adapted to be transferred from the tracks 72 to the tracks 76 and 77 from where they are run into position to be loaded by the hackers, as desired, 30 there preferably being some space between the tracks 26 and the hacked position to permit storing of, say, two cars therebetween so that empty cars will always be 35 available for loading.

40 The car 25 may have tracks 80 for receiving the cars 15 from the tracks 24 and for facilitating running said cars off onto the tracks 72. Whereas, a winch and motor unit is not necessary on the car 25 and is, 45 therefore, not shown, it is to be understood that said car could be equipped with such a unit for the purpose of pulling the cars 15 thereon should they be sufficiently bulky or weighty to make this desirable.

50 It is to be understood, of course, that in delivering the cars 15 into, through and from the dryer the doors 35 may be first suitably opened or they may, of course, be adapted to open with the movement of the 55 cars.

60 While the stacking of the bricks on the flat cars 15 may be as desired, the bricks forming the bottom course on the car are preferably stacked edgewise with a space between each brick as shown in Fig. 5. The crane fingers or elements engage beneath the next to the bottom course and between the spaced bricks forming the bot-

tom course, and are adapted to be clamped in engagement with the bricks of the bottom course to lift that course and the entire stack or pile from the drying car to be deposited at any desired point in the kiln, for example, by the crane or other means employed for that purpose.

I do not intend to limit the invention to the particular details shown or described, nor do I intend to limit it to use in transporting bricks. It may be used wherever desired with other materials and the details 75 may vary within the scope of the appended claims.

I claim:—

1. In combination, a dryer, a first track extending longitudinally along one side of said dryer, a second track extending longitudinally along the opposite side of said dryer, a plurality of tracks extending through the dryer and between said first and second longitudinal tracks, a loading station at one end of the dryer, a track extending past said loading station and between said first two tracks, a drying car operable along said last track and along the dryer tracks, a transfer car operable along said first longitudinal track for receiving the drying car from the loading station track and for delivering same selectively to the dryer tracks, and a plurality of branch tracks extending from said second longitudinal track and a second transfer car operable along said second longitudinal track for receiving the drying car from the dryer tracks and for delivering same to said branch tracks and to the loading station 100 track.

2. A transfer car for the purpose described, comprising a horizontal platform, wheels supporting said platform, motor and winch means mounted upon one end of said platform, a controller mounted upon the opposite end of said platform and a track mounted upon the platform and extending transversely across the same between said motor and winch means and said controller. 105

3. A transfer car for the purpose described comprising a wheel mounted platform, motor and winch means mounted upon one end of the platform adjacent one side thereof, a controller mounted upon the platform at the other end and substantially centrally thereof, a track mounted upon the platform and extending transversely across the same between said motor and winch means and said controller, and a weight on the platform at the motor and winch end thereof and at the opposite side of the platform from said motor and winch. 115

In witness whereof, I hereunto subscribe my name this third day of October, 1925.

CLARENCE J. WEBER.
